UNITED STATES PATENT OFFICE.

EDWARD C. SASNETT, OF WASHINGTON, DISTRICT OF COLUMBIA, ASSIGNOR, BY
MESNE ASSIGNMENTS, TO CHAS. B. FOLEY, INC., A CORPORATION OF NEW YORK.

ELECTRIC FURNACE.

Application filed September 24, 1919, Serial No. 325,838. Renewed July 7, 1927.

My invention relates to electric induction furnaces. Specifically, it relates to that type of crucible induction furnace which employs a loop of molten metal connected with the 5 pool of metal held by the crucible well below the surface thereof, the heat being generated by electric currents induced in the loop by a primary winding and core linked therewith.

10 The objects of my invention are: to produce unidirectional and thorough circulation of the metal constituting the secondary loop; to provide a form of secondary loop which can withstand a relatively high current density without being disrupted by the so-called 15 "pinch effect"; and to improve the general efficiency of the above-mentioned type of furnace.

Referring to the drawings:

20 Figs. 1 to 4, inclusive, are diagrams illustrating the theory upon which my invention is based;

25 Fig. 5 is a central vertical section of a crucible furnace embodying my invention;

Fig. 6 is a horizontal section on the line 6—6 of Fig. 5;

30 Fig. 7 is a central vertical section of another form of crucible induction furnace embodying my invention;

Fig. 8 is a plan view of the furnace shown in Fig. 7;

35 Figs. 9 and 10 are a vertical section and plan view, respectively, of a further modification; and

Fig. 11 and 12 are a vertical section and plan of another modification.

When an electric current flows through a fluid conductor, the magnetic field of the current exerts radial pressure on the conductor tending to squeeze it into a smaller compass. This pressure is concentrated at the 40 central axis of the conductor; and, under certain conditions, produces an axial flow of the metal constituting the conductor. Fig. 1 is a cross-section of a current-bearing conductor, showing the circular field of the current, the axially-directed arrows indicating the radial forces created by the current field.

45 Fig. 2 illustrates a longitudinal section of a conductor consisting of a central constricted portion connected at its ends with portions having a much larger cross-sectional area. Assuming that a current of electricity flows through this conductor, the arrows 50 show in a general way the direction and mag-

nitude of the forces created by the current field. The forces vary directly with the current density in the conductor, and are, therefore, considerably more intense in the constricted part, where the current density is 60 great as compared with the current density in the enlarged parts. Because of the fluid character of the conductor, the radial forces are transmitted along the longitudinal axis thereof. Since these axially-directed forces 65 are greater in the constricted part of the conductor, there will be an axial flow from the points of greater to the points of less pressure; that is, the fluid will move axially from the constricted towards the enlarged 70 parts, there being a return flow from the enlarged parts along the periphery of the constricted part. This circulation is represented in a general way by the arrow heads in Fig. 3.

75 The activity of the circulation will, of course, vary with the strength of the forces—that is, with the current density. When the fluid is squirted out of the restricted part with such rapidity that there is not sufficient time to replace it by a return flow of fluid from the enlarged portions, the conductor will contract, as shown in Fig. 3, resulting in an increase in the current density 80 in the contracted portion and a corresponding increase in the rate of outflow of metal 85 therefrom. This process will continue until the conductor is disrupted. The factors determining the disruption of the conductor are: the current density in the conductor, the viscosity of the material of which the conductor is formed, the frictional resistance offered by the walls confining the conductor, and the hydrostatic head of metal which the disrupting forces have to overcome.

90 In crucible induction furnaces employing a loop of metal connected with the bottom of the pool held by the crucible, the molten metal constituting the loop has, ordinarily, a rather high degree of viscosity, and the channel walls confining the loop offer considerable friction to the peripheral flow of metal. It has been found, therefore, in the operation of these furnaces that the loop of metal is disrupted at certain critical values 95 of current density below the value required to furnish that rate of heat addition necessary to employ if the furnace is to be operated at its highest efficiency. This is true even where the disruptive forces are op- 100 105 110

posed by a relatively high head of metal in the crucible.

One of the objects of my invention is to enable the use of a much greater current density in the secondary loop than has heretofore been possible without causing disruption of the metal forming the loop. To this end, I use a loop for the secondary current such as shown in Fig. 4. This figure represents diagrammatically a development of the loop, the enlarged end portions of the figure representing the bottom of the pool. As shown, the loop consists of a tapering conductor having its ends of minimum and maximum cross-section respectively. The axial forces created by the current field in this form of conductor decrease uniformly from a maximum value at the constricted end to a minimum value in the end of maximum width, in accord with the decrease in the current density. The direction of the circulation of the metal flowing axially in both directions from the point of maximum pressure is represented by the full lines and arrow heads. As shown, the metal flows along the loop centrally thereof from the point of maximum pressure—that is, the point where the constricted part of the loop joins the pool. It is obvious that the flow of metal along the loop will be fed by a flow from the pool through the restricted mouth of the loop, for this is the path of least resistance. There will be no substantial peripheral flow from the other end of the loop along the path indicated by the dotted lines, this path offering great resistance as compared with the path through the restricted part of the loop.

The forces created by the current field cannot disrupt the conductor at the point of maximum pressure—that is, at the restricted mouth of the loop, for here the loop directly joins the pool. The loop, of course, could contract at some intermediate point if the axial forces are of sufficient magnitude to squirt the metal out from that point faster than metal from the pool can flow in through the contracted mouth of the loop. But since the flow is unidirectional, the metal flowing directly from the pool to feed the mid-current in the loop, a very excessive current density would be required to cause contraction. There is no point in the loop where the metal is squirted out axially in both directions to be replaced by a peripheral flow along the walls of the channel confining the loop, as is the case in forms of loops heretofore used.

In Figs. 5 and 6, I have illustrated a crucible furnace utilizing the form of secondary loop described above. Here the loop is curved on the arc of a circle concentric with the primary coil 10. The loop, as shown, has an elongated rectangular cross-section with the major axis thereof parallel

to the axis of the primary coil. The loop has a uniform depth and a width tapering from a minimum at the point *a* to a maximum at the point *b*. The arrows indicate the circulation of the molten metal.

In the operation of this furnace, the oppositely-flowing primary and secondary currents create mutually repulsive forces which act repulsively on the primary and secondary coils. These forces have components radiating from the axis of the primary coil and components parallel to said axis. The lines of action of the latter components are inclined at acute angles to the side walls of the channel owing to the tapering form of the latter, and, therefore, have components tending to move the metal along said side walls in a clockwise direction, assisting the axial flow caused by the pressure exerted by the field of the secondary current.

Figs. 7 and 8 illustrate a crucible furnace having a pair of transverse openings 11 and 12 through which pass the legs of a laminated core 15, the primary windings 13 and 14 being located in the openings. The crucible has interior walls forming a pair of circular channels partly surrounding the primary coils. The channels have corresponding ends *a'* of minimum cross-section opening into the bottom of the crucible at the sides thereof. The other ends have a maximum cross-section and converge upwardly, opening at *b'* into a passageway connected with the bottom of the pool. In the operation of this furnace, the currents induced in the metal held by the channels flow in relatively opposite directions, and, hence, flow upwardly through the converging portions in the same direction. The motor action between the currents flowing upwardly through the converging portions, therefore, tends to move the metal upwardly through said portions. The currents flowing in the same direction attract each other, and the lines of action have components directed upwardly in said converging portions. This motor effect in conjunction with the motor effect between the primary and secondary currents previously discussed and the "pinch effect" causes the metal to flow in through the contracted mouths *a'* of the channels and to be ejected centrally into the bottom of the pool.

Figs. 9 and 10 illustrate a furnace adapted to withdraw metal from the bottom of the pool centrally thereof and to eject relatively hot metal into the bottom of the pool at the sides. Here the inner portions of the channels converge upwardly and open into a channel connected with the bottom of the pool, as in Figs. 7 and 8. The channels have their minimum cross-section, however, at the ends of the converging portions. The other ends of the channels have flaring connections with the bottom sides of the pool. The furnace is adapted to be operated with regular

- two-phase currents or with currents of the same phase. When operated with currents having the regular ninety degree phase displacement, there will be no motor action between the currents flowing in the converging portions, for the reason that half the time the currents attract and the other half repel each other, whereby their motor action is neutralized. On the other hand, where the currents have the same phase and flow in the same relative direction, the currents in the converging portions flow in opposite directions and repel each other at all times, the lines of action having components directed downwardly in the converging portions. In either case the repellent motor action between the primary and secondary currents drives the metal upwardly through the flaring mouths *d*.
- 20 Figs. 11 and 12 illustrate a furnace also adapted for operation by two-phase currents or by currents having the same phase. This furnace is like the furnace shown in Figs. 9 and 10, except that the lower portions of the channels are in alinement. It is to be noted that when this furnace is operated by currents of the same phase flowing in the same direction, there will be no current flow in the metal contained in the vertically-extending channel opening centrally into the bottom of the pool. Relatively cold metal flows down through this vertical channel to replace the metal flowing out from the horizontal contracted portion of the secondary channel.
- 35 My invention is not limited to the exact form of loop shown, but contemplates broadly the use of a loop having a minimum cross-section adjacent one of its connections with the pool.
- 40 Having fully described my invention, I claim:
1. An electric induction furnace comprising a structure lined with refractory material adapted to hold a body of molten metal in the shape of a superposed pool with a subjoined loop, the cross sectional area of which loop is a minimum at one point at which the loop joins the pool and increases gradually and continuously to a maximum at the other point at which said loop joins the pool, said furnace having a transverse opening through it within the loop, and electrical induction means threaded through said opening.
  - 55 2. An induction furnace, comprising a body of refractory material adapted to hold a pool of molten metal and having interior walls adapted to form a part of the metal into a circular loop joined with the pool and having its minimum cross-sectional area adjacent one of its points of connection with the pool, said furnace having a transverse opening therethrough within the loop, and induction means threaded through said opening.
  3. An induction furnace, comprising a body of refractory material adapted to hold a pool of molten metal and having interior walls adapted to form a part of the metal into a circular loop tapering in width from end to end, said furnace having a transverse opening therethrough and a primary winding and core located in the opening, the axis of the winding substantially coinciding with the axis of said loop.
  4. An induction furnace, comprising a body of refractory material adapted to hold a pool of molten metal and having interior walls adapted to form a part of the metal into a curved loop having a uniform depth and a width gradually increasing from end to end thereof, said furnace having a transverse opening therethrough within the loop, and induction means threaded through said opening.
  5. The process of stirring a pool of molten metal held in an electric induction furnace which consists in forming a loop of said metal depending from separate points in the bottom of said pool and applying "pinch effect" in gradually and continuously decreasing intensity from one extreme end to the other extreme end of said loop.
  6. An electric induction furnace, comprising a body of refractory material adapted to hold a pool of molten metal and having interior walls adapted to form a part of the metal into a pair of loops having corresponding ends connected at opposite sides of the pool's bottom, the other ends of the loops connected with the bottom of the pool centrally thereof through a common connection, said loops having a cross-section increasing uniformly from a minimum at their first-mentioned ends, said furnace having a pair of openings extending therethrough within the embrace of the loops, and induction means in said openings for inducing oppositely-flowing currents in the loops.
  7. An electric induction furnace, comprising a body of refractory material adapted to hold a pool of molten metal and having interior walls forming a pair of curved channels opening into the bottom of the pool, said channels having corresponding ends opening into the bottom of the pool at opposite sides thereof and the other two ends of the channels converging upwardly and having a common connection with the bottom of the pool centrally thereof, said channels decreasing uniformly in cross-sectional area from the point where they join said common connection, said furnace having a pair of openings formed transversely therethrough and partly surrounded by said channels, and induction means threaded through said openings for inducing oppositely-flowing currents in the metal held by said channels.
  8. An electric induction furnace, comprising

ing a body of refractory material adapted to hold a pool of molten metal and having interior walls forming a pair of curved channels opening into the bottom of the pool and located substantially in the same vertical plane, two corresponding ends of the channels opening into the bottom of the pool at opposite sides thereof, and the other two ends of the channels converging upwardly

and opening into a channel connected with the bottom of the pool centrally thereof, the cross-sectional area of the channels decreasing from a minimum at their converging ends, said furnace having a pair of openings formed transversely therethrough and partly 15 surrounded by said channels, and induction means threaded through said openings.

EDWARD C. SASNETT.
